DESIGN FOR A RING

Oscar Heyman, New York, N. Y., assignor to Oscar Heyman and Brothers, Inc., a corporation of New York

Application May 6, 1937, Serial No. 69,191

Term of patent 14 years

To all whom it may concern:

Be it known that I, Oscar Heyman, a citizen of the United States, residing at New York city, in the county of New York and State of New York, have invented a new, original, and ornamental Design for a Ring, of which the following is a specification, reference being had to the accompanying drawing, forming part thereof.

is a plan view, and Figure 3 is a side view of a ring, showing my new design.

I claim:

The ornamental design for a ring, as shown.

OSCAR HEYMAN.
